(57) **CLAIM**

The ornamental design for a label and label roll set as shown and described herein.

DESCRIPTION

FIG. 1 is a front isometric view of a first embodiment of a label and label roll set, showing my new design;

FIG. 2 is a rear isometric view of the label and label roll set of FIG. 1;

FIG. 3 is an elevational view of a front face of the label and label roll set of FIG. 1;

FIG. 4 is an elevational view of a rear face of the label and label roll set of FIG. 1;

FIG. 5 is an elevational view of a bottom edge of the label and label roll set of FIG. 1;

FIG. 6 is a top plan view of the label and label roll set of FIG. 1;

FIG. 7 is an elevational view of a left side edge of the label and label roll set of FIG. 1, an elevational view of a right side edge of the label and label roll set being identical to the elevational view of the left side edge;

FIG. 8 is a front isometric view of a second embodiment of a label and label roll set;

FIG. 9 is a rear isometric view of the label and label roll set of FIG. 8;

FIG. 10 is an elevational view of a front face of the label and label roll set of FIG. 8;

FIG. 11 is an elevational view of a rear face of the label and label roll set of FIG. 8;

FIG. 12 is an elevational view of a bottom edge of the label and label roll set of FIG. 8;

FIG. 13 is a top plan view of the label and label roll set of FIG. 8;

FIG. 14 is an elevational view of a right side edge of the label and label roll set of FIG. 8, the elevational view of a left side edge of the label and roll set being a mirror image of the elevational view of the right side edge;

FIG. 15 is a rear isometric view of a third embodiment of a label and label roll set;

FIG. 16 is a front isometric view of the label and label roll set of FIG. 15;

FIG. 17 is an elevational view of a front of the label and label roll set of FIG. 15;

FIG. 18 is an elevational view of a rear of the label and label roll set of FIG. 15;

FIG. 19 is an elevational view of a left side of the label and label roll set of FIG. 15, the elevational view of a right side of the label and label roll set being a mirror image of the elevational view of the left side;

(Continued)

FIG. 20 is a top plan view of the label and label roll set of FIG. 15;
 FIG. 21 is an elevational view of a bottom of the label and label roll set of FIG. 15;
 FIG. 22 is a front isometric view of a fourth embodiment of a label and label roll set;
 FIG. 23 is a rear isometric view of the label and label roll set of FIG. 22;
 FIG. 24 is an elevational view of a front face of the label and label roll set of FIG. 22;
 FIG. 25 is an elevational view of a rear face of the label and label roll set of FIG. 22;
 FIG. 26 is an elevational view of a bottom edge of the label and label roll set of FIG. 22;
 FIG. 27 is a top plan view of the label and label roll set of FIG. 22;
 FIG. 28 is an elevational view of a left side edge of the label and label roll set of FIG. 22, the elevational view of a right side edge of the label and label roll set being identical to the elevational view of the left side edge;
 FIG. 29 is a front isometric view of a fifth embodiment of a label and label roll set;
 FIG. 30 is a rear isometric view of the label and label roll set of FIG. 29;
 FIG. 31 is an elevational view of a front face of the label and label roll set of FIG. 29;
 FIG. 32 is an elevational view of a rear face of the label and label roll set of FIG. 29;
 FIG. 33 is an elevational view of a bottom edge of the label and label roll set of FIG. 29;
 FIG. 34 is a top plan view of the label and label roll set of FIG. 29;
 FIG. 35 is an elevational view of a right side edge of the label and label roll set of FIG. 29, the elevational view of a left side edge of the label and label roll set being a mirror image of the elevational view of the right side edge;
 FIG. 36 is a rear isometric view of a sixth embodiment of a label and label roll set;
 FIG. 37 is a front isometric view of the label and label roll set of FIG. 36;
 FIG. 38 is an elevational view of a front of the label and label roll set of FIG. 36;
 FIG. 39 is an elevational view of a rear of the label and label roll set of FIG. 36;
 FIG. 40 is an elevational view of a left side of the label and label roll set of FIG. 36, an elevational view of a right side of the label and label roll set being a mirror image of the elevational view of the left side;
 FIG. 41 is a top plan view of the label and label roll set of FIG. 36; and,
 FIG. 42 is an elevational view of a bottom of the label and label roll set of FIG. 36.

The broken lines (where present) in all FIGS. illustrate portions of the label and label roll set that form no part of the claimed design. In addition, the stippling pattern (where present) in all FIGS. represents a contrast in appearance.
